UNITED STATES PATENT OFFICE.

RAUL PATERAS PESCARA, OF PARIS, FRANCE.

FLUID-ACTUATED COMPRESSOR.

Application filed June 2, 1927, Serial No. 195,981, and in France June 17, 1926.

My invention relates to compressors which are actuated by a fluid under pressure, and one of its objects is to utilize the energy of a compressed fluid for producing the compression of another fluid, either of the same or of a different nature but under different conditions of temperature and pressure and with a high output.

- Another object of my invention resides in 10 the adaptation of a device of the character indicated to the apparatus disclosed and claimed in my copending applications Serial No. 177,938, filed March 24, 1927; Serial No. 177,939, filed March 24, 1927; Serial No. 181,553, filed April 6, 1927; Serial No. 181,554, filed April 6, 1927; Serial No. 181,555, filed April 6, 1927; Serial No. 181,556, filed April 6, 1927, and Serial No. 195,980, filed June 2, 1927.
- 20 Other objects of the invention will be obvious to those skilled in the art to which it relates in the following description taken in connection with the accompanying drawing, in which—
- 25 Fig. 1 is an elevation of the device with parts in section;

Fig. 2 is a section along the line 10—11 of Fig. 1; and

30 Fig. 3 is a broken section taken along the lines 12, 13, 14, 15 in Fig. 2.

Referring to the drawing, a motor cylinder 16 has disposed concentrically at each end thereof, compressing cylinders 17 and 18. Within said compressing cylinders are disposed pistons which extend into the common motor cylinder 16, only one of said pistons being shown at 19.

35 The piston 19 carries two pivot bearings 20 disposed at diametrically opposite points, 40 only one of which is shown. The construction is the same for the piston in cylinder 18.

In the center of the machine are disposed 45 two levers 21, 22 pivoted on an axis perpendicular to the common axis of cylinders 16, 17, 18 the opposite arms of said levers terminating in pivot connections 23, 24, 25, 26.

50 Four connecting rods 27, 28, 29, 30 connect the pivot connections 20 of the pistons 19 to the pivot connections 23, 24, 25, 26 of levers 21, 22. A mechanical connection is thus assured between the pistons which maintains synchronism of their movements in opposite directions.

55 Steam, for example, is admitted to cylinder 16 through a supply pipe 38 and through

steam chambers 39 and 40 opening into said cylinder on the opposite sides thereof. Each of said chambers is provided with identical distributing devices only one of which is shown.

60 A circular oscillating plate valve 31 is provided with slots 32, 33, 34, adapted to coincide with slots 35, 36, 37 in a stationary valve seat 41 said last mentioned slots communicating with the interior of cylinder 16. The 65 valve 31 is pivoted on a shaft 42 which is integral with the valve seat 41. An abutment 43 is made integral with the valve 31 and projects outwardly therefrom.

The lever 21 is pivoted on a collet 44 carried by the valve 31 by means of a sleeve 45 which penetrates the steam box 39 through a suitable packed joint 46. The sleeve 45 is provided with a notch which receives the abutment 43 of the valve 31 in such wise that 70 the edges 47, 48 of said notch can come in contact with the sides of the abutment 43. The lever 21 is thus free to turn with respect to the valve 31.

75 An exhaust pipe 49 is provided which may open into the atmosphere or be connected to a condenser and communicates with the interior of cylinder 16 by an orifice 50, in which a valve 51 is adapted to be seated. The stem of said valve is integral with a piston 53 80 whose diameter is greater than the effective diameter of the valve 51.

85 The piston 53 slides in a cylinder 54 which terminates in a head 55. The space included between the piston 53, the cylinder 54 and its 90 head 55 is provided with four orifices of which 56 and 57 communicate with the openings 58 in the valve seat 41 through tubes 59 and of which 60 and 61 open into the cylinder 16 near the extremities thereof at 162, 163 by 95 means of the tubes 62, 63. A spring 65 bears against the piston 53 in a way to provoke the raising of the valve 51.

100 The valve 31 is provided with another elongated opening 66 which can be superposed on the circular orifice 58 of plate 41, during angular movement thereof. It will be noted that in order to obtain coincidence of the openings 32, 33, 34 in the valve 31 with those of 35, 36, 37 in the plate 41, it is necessary 105 that the plate 31 turn through the angle 67 in the direction of the arrow 68. Under these conditions the orifice 58 will have been covered by the opening 66 slightly before the closing of the orifices 35, 36, 37.

The distribution of air, for example, takes place in the compressing cylinders 17, 18 by means of automatic inlet check valves 69, 70 and outlet check valve 71 only one set being shown. Two suitable pipes 72, 73 conduct the air compressed to a tank for storing or to an apparatus for direct consumption.

The operation of the apparatus is as follows:

- 10 Figs. 1, 2 and 3 represent the positions the different parts of the apparatus occupy when the pistons 19 have arrived at the end of their expanding stroke toward the motor end and at the end of their compression stroke toward the compressor end. The pistons 19 will return to the center of the apparatus under the impulse of compressed air which remains in the compressing cylinders.

At this moment the extremities 162, 163 of 20 the tubes 62, 63 have just been uncovered by the pistons 19 in such wise that the prevailing pressure on the interior of cylinder 54 is the low pressure of that in pipe 49, the spring 65 maintaining the valve 51 raised.

25 The pistons 19 in returning to the center of the apparatus push back the expanded steam contained between them through the orifice 50 and the pipe 49. At the beginning of their movement the distributing valve 31 remains motionless until the edge 47 of the notch of sleeve 45 which turns in the direction of the arrow 68 meets the abutment 43 of the valve 31. Said valve is then displaced with the lever 21 and the pushing back of the steam 35 normally continues.

At a predetermined moment the opening 66 of the valve 31 meets the orifice 58 of the valve seat 41. Steam under pressure then penetrates the cylinder 54 through tubes 59 and the orifices 56 and 57. The said steam cannot escape through the tubes 62, 63 due to the fact that their openings 162, 163 are at this instant closed by the pistons 19. The piston 53 is then thrust toward the cylinder 45 16 and the valve 51 becomes seated. The exhausting of the steam terminates and that which remains in cylinder 16 between the pistons becomes compressed.

50 This compression continues since the elongated opening 66 assures communication between the chamber 39 and the cylinder 54 up to the end of the stroke. The valve 51 cannot be raised since the diameter of the piston 53 is greater than the effective diameter 55 of the said valve.

The openings are so designed and regulated that the pressure of the steam attains the value of that prevailing in the chamber 39 at the moment when the openings 32, 33, 34 of 60 valve 31 meet the openings 35, 36, 37 of the valve seat 41. The movement of the pistons 19 continues by their inertia and does not cease until there is complete coincidence of the said openings.

65 Under the impulse of the pressure of the

steam, the pistons such as 19 then set out again in opposite directions moving away from each other from the center of the machine. From the beginning of their movement the distributing valve 31 remains motionless 70 which assures the admission at a constant pressure of a suitable quantity of steam. When the edge 48 of the sleeve 45 meets the stop 43 of the valve 31, the latter is carried along in the direction opposite to that of the arrow 68 and consequently recovers the orifices 35, 36, 37 of the valve seat 41. The steam continues then to expand in the cylinder 16.

During all this time the valve 51 has remained seated by the steam contained in the cylinder 54 which cannot escape until the pistons such as 19 uncover the orifices 162, 163 of the tubes 62, 63. It is then that the piston 53 is urged by the spring 65, raising the valve 51 and permitting the expanded steam to exhaust through the orifice 50 and the pipe 49. This cycle of operation continues on indefinitely as long as steam is applied to the cylinder 16.

In the compressing cylinders the air is alternately compressed and partially pushed back through the check valves 71, the part remaining in the dead spaces expanding thereafter for assuring the return of the pistons 19. After this expanding, which is much 95 shorter in duration than the compressing stroke, the pistons 19 draw in a new quantity of fresh air through the check valves 69 and 70 and the operation is repeated.

Obviously many variations in the "modus operandi" of my device may be resorted to without departing from the scope of my invention. For example, compression of the air might take place in steps by utilizing the device disclosed in my copending application 100 Serial No. 195,980, filed June 2, 1927. Preferably the motor fluid employed will constitute part of the air compressed in the stages of the compressor and admitted to the motor cylinder after a thermic enrichening by re-heating. I prefer to produce the said re-heating operation by combustion of a combustible fluid on the interior of the apparatus either partially or totally by utilizing one of the distributing valve plates for its introduction into the cylinder.

Having thus described my invention what I claim as new and desire to secure by Letters Patent is—

1. In a compressor of the type described a 120 plurality of compressing cylinders, a common motor cylinder coaxially disposed with respect thereto, a piston in each of said compressing cylinders, a second driving piston integral with each of said first mentioned pistons and extending into said common cylinder, a stud shaft mounted on said motor cylinder midway between said compressing cylinders, a plurality of two armed levers mounted loosely on said stud shaft, means for piv- 125

totally connecting each extremity of said levers pivotally to said pistons on the compressing portion thereof whereby synchronous movement of said pistons is assured, 5 means for supplying a fluid under pressure to said motor cylinder and means operated by said levers for causing said fluid to drive said pistons in opposite directions at regular intervals.

10 2. In a compressor of the type described a plurality of compressing cylinders, a common motor cylinder coaxially disposed with respect thereto, a piston in each of said compressing cylinders, a second driving piston integral with each of said first mentioned pistons and extending into said common cylinder, synchronizing means for pivotally interconnecting said pistons, means for supplying a fluid under pressure to said motor 15 cylinder, means for controlling the admission of said fluid into said motor cylinder operated by said synchronizing means, an exhaust port for said motor cylinder and pressure operated means for closing said exhaust 20 port responsive to said fluid when said pistons have attained either end of their stroke.

3. In a compressor of the type described a plurality of direct acting compressing pistons, a cylinder therefor, admission openings in 30 said cylinder, a rotary valve plate covering said openings, an enclosed chamber surrounding said plate, means for supplying said chamber with a fluid under pressure, a plurality of openings in said plate, means operated by said 35 pistons for causing the openings in said plate to coincide with the openings in said cylinder when said pistons have attained a certain position in their stroke, an exhaust port for said cylinder, a valve for said exhaust port, a 40 spring for holding said valve in normal open position, pressure responsive means for closing said valve, said means being provided with an orifice in communication with the extremity of said cylinder which is adapted to 45 be uncovered only when said piston has attained one end of its stroke and a second orifice in communication with said chamber through said rotary plate.

4. In a compressor of the type described a plurality of direct acting pistons, a cylinder therefor, admission openings in said cylinder, a rotary valve plate covering said openings, an enclosed chamber surrounding said plate, means for supplying said chamber with a 55 fluid under pressure, a plurality of openings in said plate, a loose connection device operated by said pistons for causing the openings in said plate to coincide with the openings in said cylinder when said pistons have 60 attained a certain position in their stroke, an exhaust port for said cylinder, a valve for said exhaust port, a spring for holding said valve in normal open position pressure responsive means for closing said valve provided with an orifice in communication with

the extremity of said cylinder which is adapted to be uncovered only when said piston has attained one end of its stroke and a second orifice in communication with said chamber through said rotary plate. 70

5. In a compressor of the type described a plurality of direct acting compressing pistons, a cylinder therefor, admission openings in said cylinder, a rotary valve plate covering said openings, an enclosed chamber surrounding said plate, means for supplying said chamber with a fluid under pressure, a plurality of openings in said plate, means operated by said pistons for causing the openings in said plate to coincide with the openings in said cylinder when said pistons have attained a certain position in their stroke, an exhaust port for said cylinder, a valve for said exhaust port, a spring for holding said valve in normal open position, a piston on 75 said valve, a cylinder for said piston, the diameter of said piston being greater than the effective diameter of said valve an orifice in said cylinder in communication with the extremity of said first mentioned cylinder 80 adapted to be uncovered only when said first mentioned piston has attained one end of its stroke and a second orifice in communication with said chamber through said rotary plate.

6. In a compressor of the type described a plurality of direct acting pistons, a cylinder therefor, admission openings in said cylinder, a rotary valve plate covering said openings, an enclosed chamber surrounding said plate, means for supplying said chamber 95 with a fluid under pressure, a plurality of openings in said plate, an abutment on said plate, a synchronizing device adjacent said plate connected to said pistons, a sleeve on said synchronizing device having a notched 100 portion fitting over said abutment whereby the openings in said plate may be made to coincide with the openings in said cylinder when said pistons have attained a certain position in their stroke, an exhaust port for said 105 cylinder, a valve for said exhaust port, a spring for holding said valve in normal open position, pressure responsive means for closing said valve provided with an orifice in communication with the extremity of said cylinder 110 which is adapted to be uncovered only when said piston has attained one end of its stroke and a second orifice in communication with said chamber through said rotary plate. 115

7. In a fluid compressor of the type described the combination of a plurality of direct actuated direct acting compressing pistons, means operated by said pistons for supplying said pistons with a common operating fluid under pressure at regular intervals, a normally open exhaust valve for said operating fluid and means responsive to said operating fluid opposing the opening of said exhaust valve at regular intervals for the purpose set forth. 120

8. In a fluid compressor of the type described the combination of a plurality of direct actuated direct acting compressing pistons, an oscillating valve plate operated by 5 said pistons for supplying said pistons with a common operating fluid under pressure at regular intervals, a normally open exhaust valve for said operating fluid and means under control of said oscillating valve plate responsive to said operating fluid opposing the 10 opening of said exhaust valve at regular intervals for the purpose set forth.
9. In a fluid compressor of the type described the combination of a plurality of direct actuated direct acting compressing pistons, an oscillating valve plate operated by 15 said pistons for supplying said pistons with a common operating fluid under pressure at regular intervals, a normally open exhaust valve for said operating fluid and means under control of said oscillating valve plate and 20 said pistons responsive to said operating fluid opposing the opening of said exhaust valve at regular intervals for the purpose set forth.
10. In a fluid compressor of the type described the combination of a plurality of direct actuated direct acting compressing pistons, an oscillating valve plate operated by 25 said pistons for supplying said pistons with a common operating fluid under pressure at regular intervals, a normally open exhaust valve for said operating fluid and means under control of said oscillating valve plate re-
- valve for said operating fluid, an auxiliary piston opposing the opening of said exhaust valve, means associated with said oscillating plate for supplying said auxiliary piston with a portion of said operating fluid at regular intervals and means under control of said pistons for releasing said operating fluid in contact with said auxiliary piston for the 40 purpose set forth.
11. In a fluid compressor of the type described the combination of a plurality of direct actuated direct acting compressing pistons, an oscillating valve plate operated by 45 said pistons for supplying said pistons with a common operating fluid under pressure at regular intervals, a normally open exhaust valve for said operating fluid, an auxiliary piston opposing the opening of said exhaust valve, means associated with said oscillating plate for supplying said auxiliary piston with a portion of said operating fluid at regular intervals and means under control of said pistons for releasing and discharging 50 said operating fluid in contact with said auxiliary piston into the main bulk of operating fluid when said main bulk of operating fluid has expanded to a predetermined degree for the purpose set forth.

In testimony whereof I have signed my name to this specification at Paris, France, this 21st day of May, 1927.

RAUL PATERAS PESCARA.
